UNITED STATES PATENT OFFICE.

WILHELM LOMBARDO, OF BUDAPEST, AUSTRIA-HUNGARY, ASSIGNOR TO
JOSEF EISELE, OF BUDAPEST, AUSTRIA-HUNGARY.

IMPLEMENT FOR CLEANING BOILER-TUBES, &c.

SPECIFICATION forming part of Letters Patent No. 691,475, dated January 21, 1902.

Application filed April 11, 1901. Serial No. 55,345. (No model.)

To all whom it may concern:

Be it known that I, WILHELM LOMBARDO, a subject of the Emperor of Austria-Hungary, residing at Budapest, in the Empire of Austria-Hungary, have invented a certain new and useful Improved Implement for Cleaning Boiler-Tubes and the Like, (for which I have applied for a patent in Hungary, Germany, England, France, and Belgium,) of which the following is a specification.

The present invention relates to an implement for removing incrustation from the exterior surfaces of fire-tubes of steam-boilers, cooking and distilling apparatus, and the like.

15 The said implement consists of a number of hammer-shaped scrapers oscillating upon a rigid or flexible band or rod and held by spring-pressure in a position perpendicular to the band or rod.

20 The construction and action of the device is illustrated in the annexed drawings.

Figures 1 and 2 represent a front and side elevation thereof, respectively; Figs. 3 and 4, sections on a larger scale on the lines A B, 25 Fig. 1, and C D, Fig. 2, respectively, while Fig. 5 shows the action of the device.

As will be seen from the drawings, a number of hammer-shaped scrapers *b*, each having two sharp faces *c c*, are pivoted to a band 30 or rod *a* of suitable breadth, which may consist of several parts linked together in the manner of a link chain. The said hammers *b* are so mounted that when the rod or band *a* is in a vertical position their axes of oscillation and faces *c c* are horizontal. Each of the hammers or scrapers *b*, adapted to oscillate on the pins *d*, is normally held in a horizontal position by a helical spring *g*, passing through the shank-lever *f* and surrounding 35 the pin *d*, the flat ends *h* of the said springs bearing against the rod *a*; but the scrapers can yield to pressure, acting in one or the other direction of rotation.

In use the device is introduced from above 40 into the spaces between the tubes *r*, Fig. 5, and moved alternately upward and downward. On the latter movement taking place each of the scrapers will first strike against the crest of a tube, then slowly revolve in an

upward direction, and in doing so clean the 50 upper half of the tube. On the continued downward movement of the rod the scraper will slide off the first tube and strike with the greatest spring-power against the next tube below it (see position indicated by dotted 55 lines) and will also slide off this, and so on. During the upward movement of the rod the action is similar, the scrapers sliding from the lower tubes and striking against the lowest portion of the next tube above, cleaning the 60 lower parts of the tubes during the subsequent phases of motion.

As will be seen, the apparatus acts at the same time as a hammer and scraper and rapidly and effectually removes all deposit from 65 the tubes without deteriorating the period of action of the latter.

Instead of being operated by hand the apparatus can be operated by a motor driven by means of electricity, steam, or compressed 70 air, in which case the reciprocating movement of the scraper-carrier can be obtained by means of a suitable crank or eccentric mechanism with the aid of suitable transmission-gear. The motor may be placed upon the 75 tubes and provided with devices for obtaining automatically the movement desired.

What I claim, and desire to secure by Letters Patent, is—

In a device for cleaning the exterior surface 80 of boiler-tubes, the combination of a longitudinally-reciprocatory power-transmitter, a scraper-arm, a pin extending loosely through a passage in the scraper-arm and having its ends secured in lugs or flanges extending outwardly from one face of the power-transmitter, and a spring extending through a passage in said scraper-arm and having its ends coiled about said pin and bearing against the power-transmitter on opposite sides of the scraper-arm. 85

In testimony whereof I have hereunto set my hand in the presence of two witnesses.

WILHELM LOMBARDO.
